UNITED STATES PATENT OFFICE.

EDWARD P. CUSHMAN, OF LYNN, MASSACHUSETTS.

BAG-TAG OR CARD-RECEPTACLE.

SPECIFICATION forming part of Letters Patent No. 554,171, dated February 4, 1896.

Application filed June 7, 1895. Serial No. 551,968. (No model.)

To all whom it may concern:

Be it known that I, EDWARD P. CUSHMAN, a citizen of the United States, residing at Lynn, in the county of Essex and State of Massachusetts, have invented certain new and useful Improvements in Bag-Tags or Card-Receptacles, of which the following is a specification, reference being had therein to the accompanying drawings.

10 My invention relates to receptacles for name-plates or cards, and particularly to that class of receptacles known as "bag-tags," which are intended to be attached to a grip, or to luggage of any sort, so that the same may be 15 readily identified.

The tag now in general use consists of a case or sheath usually made of two pieces of leather stitched together at their edges and one end and left open at the other end to permit 20 the card bearing the name or address to be inserted. One side of the case thus constructed has a sight-opening formed therein through which the card within may be read, the face of the card being usually protected by 25 a plate of mica or other transparent material.

The tag constructed as above described is objectionable in that the card bearing the name and address is too conspicuous, and it is with the intention of overcoming this objection 30 that I have invented the device which I shall now describe in detail, reference being had to the accompanying drawings, which form part of this specification, in which—

Figure 1 is an enlarged plan view of my invention. Fig. 2 is a longitudinal sectional view on line 2 2 of Fig. 1. Fig. 3 is a view similar to Fig. 2 of a modified form of my invention. Fig. 4 is a view of a second modification, and Fig. 5 is a sectional view.

40 Referring to the drawings by letter, *a a'* denote the two members of which the tag is formed, said members being preferably of leather and being stitched or otherwise fastened together at their sides and one end and 45 being left open at the other for the reception of the card or name-plate *b* and the mica covering-plate *c*. The members *a a'* are somewhat elongated at the open end of the case to 50 form ears *d*, which are punched to provide openings through which the securing-strap *e* is passed.

A tongue or flap *f* is secured to the member *a*, so as to cover the sight-opening *g* formed therein, said tongue *f* being preferably formed by stamping it out of the member *a*, as shown 55 in the drawings. The said tongue *f* normally lies flat and covers the opening *g* in the case, so as that the name on the inclosed card is concealed; but when it is desired to read the name to identify the luggage the flap or tongue *f* 60 may be raised, so as to uncover the opening *g*.

It is obvious that the tongue *f*, being struck out of the member *a*, will, when in its normal position, lie within the opening and flush with the surface of said member *a*, and therefore 65 will not render the tag or case thick and cumbersome.

When the tongue *f* is stamped out of the member *a*, as shown, I find that there is sufficient friction between the edges of the tongue 70 *f* and the opening *g* to retain the said tongue *f* in its normal position within the sight-opening *g*; but in order that it may be more securely held therein I may provide the locking means shown in Fig. 3. In the construction 75 therein shown I give the tongue *f* a dovetail or undercut at *f'* instead of a straight or vertical cut, as in the form shown in Fig. 1. It is apparent that by thus cutting the end of tongue *f* at an angle the said tongue will be 80 locked in the opening *g* against accidental displacement. A slight flexure or bending of the tag, however, will be sufficient to throw the undercut end *f'* out of the opening *g*.

In Fig. 4 I have shown the tongue as provided with a snap-fastener of the ordinary type, the stud or male member *h* of the fastener being secured in the back member *a'* of the case, while the female member *h'* is secured in the end of the tongue *f*. It will be 85 understood, of course, that in event of using the fastener just described the stud portion *h* would project up through the card or name-plate and the transparent covering-plate, and not only serves to lock the tongue *f* in position, 90 but also secures the name-plate or card *b* and the transparent covering-plate *c* against accidental displacement. 95

It is obvious that my invention may be applied to other articles than bag-tags and may 100 be used wherever it is desirable to temporarily conceal a name-plate or card and I do

not, therefore, limit my invention to the particular use and application herein shown and described.

Having thus described my invention, I 5 claim and desire to secure by Letters Patent—

1. A bag-tag or card-receptacle composed of two members fastened together at their sides and one end, one of said members having a sight-opening formed therein, a concealing-tongue stamped from one of said members normally closing said sight-opening, and means for securing said tongue in normal position.

15 2. A bag-tag or card-receptacle having a sight-opening formed in one side thereof, a concealing-tongue normally covering said sight-opening, and means for securing said

tongue in its normal position, said means for securing the card or name-plate within the 20 receptacle.

3. A bag-tag or card-receptacle composed of two members fastened together at their sides and one end, one of said members having a sight-opening formed therein, and a 25 tongue formed integral with one of said members and normally closing the sight-opening, said tongue having an undercut end, as and for the purposes set forth.

In testimony whereof I affix my signature 30 in the presence of two witnesses.

EDWARD P. CUSHMAN.
